FUNNEL WITH SUPPORTING ELEMENT HAVING MEANS FOR FITTING DIFFERENT SIZED FILLING SPOUTS

Max T. Bentzen, Minneapolis, Minn., assignor to General Metalware Company, Minneapolis, Minn., a corporation of Delaware

Application October 21, 1946, Serial No. 704,544

5 Claims. (Cl. 226—31)

1

The present invention relates to a funnel construction which is particularly adaptable for rigid attachment to vessels with which it is to be used. The funnels herein illustrated are especially adapted to be used with vessels having removable cap closures, such as automobile and tractor fuel tanks and the like.

In many motor vehicles, such as tractors and portable power units, the fuel tanks are located adjacent or above the motor. The filling of the fuel tanks of such units is hazardous because any spilled fuel falls upon the motor where it is likely to be ignited by the heat of the motor or the exhaust manifold. The hazard is increased when the filling is done in the field, since fuel is usually transferred by pails or cans which must be balanced in an elevated position while the fuel is poured into the fuel tank of the motor unit. Wind, unsteady conditions, the weight of the cans or pails, and insecure funnels contribute to the hazard.

In United States Patent No. 2,168,395 issued August 8, 1939, there is disclosed a funnel construction which is suitable for use where the above problem is presented. However, the funnel there disclosed is designed to fit a single sized filling spout. The filling spouts on fuel tanks for different types of tractors, automobiles and trucks may vary in size, and accordingly where the construction disclosed in the above patent is employed, it is found necessary to have an individual funnel for each size filling spout.

The present invention provides a funnel construction which makes the funnel adaptable for use on a number of different size filling spouts and accordingly a single funnel can be used for different size filling spouts and it is not necessary to have an individual funnel for each size spout.

It is therefore an object of the present invention to provide a funnel construction adapted to be rigidly attached to a filling spout, which funnel construction is adapted to fit a plurality of filling spouts.

This and other objects of the invention will be more fully apparent from the following description of the invention with particular reference to the drawings in which

Figure 1 is a fragmentary side elevational view, partly in section, illustrating the present invention as applied to a small filling spout;

Figure 2 is a similar section of the invention as applied to a medium sized filling spout;

Figure 3 is a similar view of a funnel applied to a large sized filling spout;

Figure 4 is a bottom view of the funnel showing

the details of the means for attaching the funnel to the filling spout;

Figure 5 is an elevation of a fragment of the funnel showing further details of the attaching means;

Figure 6 is a perspective view showing the type of filling spout commonly found on automobiles, tractors and trucks, to which the present funnel construction is adapted to be attached, showing the various diameters of filling spouts which the funnel will fit;

Figure 7 is a plan view showing the shape of the funnel support and locking member at its first stage of manufacture;

Figure 8 is a sectional view in the direction of arrows 8—8 of Figure 7, showing the second stage of manufacture;

Figure 9 is an elevational view, partly in section, showing the third stage of manufacture; and

Figure 10 is a sectional elevational view showing the fourth stage of manufacture with the support and locking member assembled to the funnel parts.

With reference to Figure 1, the funnel comprises a frustoconical section 11 and a cylindrical spout section 12 which may be integral with the frustoconical section but which preferably is formed separately and suitably attached to the frustoconical section, such as by welding, rolling, soldering or the like. The junction of the spout and the frustoconical section comprises a recessed shoulder 13 which is adapted to receive a wire cloth 14 which is held in place by means of a snap ring 15.

The funnel supporting and attaching element generally designated 30 are composed of a cylindrical portion 16 from which various segments extend to form the locking fingers 17, 18 and 19 and the bearing members 20 (Figure 4). As shown in Figure 4, the locking fingers 17 have bearing members 20 immediately above them, whereas locking members 18 and 19 are disposed at an angle thereto. The bearing members 20 are shaped as shown in Figures 1, 2, 3 and 5 to provide a plurality of step-like bearing surfaces 21, 22 and 23.

As shown in Figure 1 wherein the funnel is attached to a small size filling spout 24, the smallest size locking fingers 17 bear under the inturned cam edge 25 of the filling spout. At the same time the upper edge of the filling spout bears on the first bearing surface 21. As will be evident from the filling spout shown in Figure 6, 55 the funnel is attached to the filling spout by pass-

ing locking fingers 17 down through openings 26 in the upper lip of the filling spout, after which the entire funnel is rotated until the locking fingers bear beneath the inturned cam edge 25 and rotation of the funnel brings the top of the filling spout to bear on the bearing surface 21 of the funnel and the funnel is accordingly rigidly fastened to the filling spout.

In Figure 2 a medium size filling spout is illustrated, generally designated 24a having an inturned cam edge 25a. This cam edge 25a of the filling spout cooperates with locking fingers 18 of the funnel and bearing surface 22 to attach the funnel to the filling spout in much the same manner as that of Figure 1 when the funnel is set in place and rotated.

In Figure 3 there is illustrated a large size filling spout generally indicated at 24b and having an inturned cam edge 25b which cooperates with locking fingers 19 of the funnel and bearing surface 23 to attach the funnel to the spout when the funnel is inserted in the spout and turned.

The attaching means may be fastened to the funnel in any suitable manner. Thus, the cylindrical section 16 may be suitably fastened by riveting, soldering, welding and the like to the adjacent spout portion 12. Likewise, the bearing members 20 may be fastened near their upper portions to the corresponding frustoconical section 11 in any of the above ways.

Figure 5 illustrates in a single figure the varicus locking fingers and the bearing surfaces and their relative positions. From this figure it will be seen that locking fingers 18 and 19 extend outwardly approximately at the level of bearing areas 21 and 22 and thus do not interfere with the operation of the device in any sized filling spout.

The attaching means may be very easily made from a piece of tubing which is partially slit longitudinally to form the segments from which the locking fingers 17, 18 and 19, as well as the bearing members 20 are formed. These various locking fingers and bearing members may be suitably shaped by bending the segments outwardly and then stamping or by other suitable operations.

An alternative method of manufacturing the funnel support and locking member and a method of assembly to the funnel parts is illustrated in Figures 7-10. As illustrated in these figures, the funnel supporting and attaching member generally designated 30 may be made very easily by stamping from flat steel. The metal is first blanked out by punching to the shape shown in Figure 7. In this stage the locking fingers, which are still rudimentary and flat, are shown at 17, 18 and 19, and the support portions 20 which are later formed to provide step seats 21, 22 and 23 are also flat. Figure 8 illustrates the next step, wherein fingers 18 are bent down, the remainder of the blank being still flat. The third step is shown in Figure 9, wherein the central aperture 31 is drawn down to cylindrical shape at 32. At this stage locking fingers 17 are a part of the cylindrical opening 32. Also, in this operation members 20 are bent to present the step seats 21, 22 and 23 and locking fingers 18 and 19 are formed to their final position. In the next drawing operation, the locking fingers 17 are bent out to the positions shown in Figure 10, and the unit 30 can then be assembled to the spout section 12 and the funnel section 11. Note that the spout has an outwardly rolled beading at 33 which serves to locate it accurately in the cylindrical opening 32 of the member 30. The funnel part 11 has an in-

tegral end flange 34 which slips into the upper end of spout 12, and at the same time the outer surface of the conical part 11 bears against the upper ends of fingers 20. The assembly is then spot welded at 35 and is consequently firmly held together. Then the entire unit is cleaned and galvanized, the zinc of the galvanizing process serving additionally to hold the assembled parts into a unitary whole which has great strength and ruggedness.

As will be apparent from Figures 1 to 3, there is ample opportunity for escape of air or vapors from the container being filled through the openings 26 in the upper lip of the filling spout as well as through the spaces between the bearing members 20.

It will be apparent from the above description that the present invention provides a funnel construction having means for adapting it to a plurality of filling spout sizes and makes possible the use of a single funnel to file a variety of different filling spouts. While various modifications of the invention have been described, it will be apparent that other modifications are possible without departing from the spirit of the invention as defined in the following claims.

What I claim is:

1. A funnel construction comprising a conical section joined with a spout section, an external supporting member rigidly attached on the outside of said sections adjacent their junction, said supporting member being formed with a plurality of bearing areas of varied transverse dimension at different levels and outwardly protruding locking fingers of correspondingly varied transverse dimension in spaced relation below each bearing area level.
2. A funnel construction for use upon fluid receiving fuel tank filler necks of varying diameter comprising a conical section joined to a spout section, a funnel support at the junction of said sections and on the outer surface thereof comprising a plurality of step-like members in spaced relation around the funnel, the steps of said members forming bearing areas at successively higher levels and of increased radial dimension for resting upon filler necks of increased diameter, and outwardly protruding locking fingers of correspondingly varied transverse dimension in spaced relation below each bearing area level.
3. A funnel construction comprising an assembly of a conical section and a spout section, an external member disposed outside of said assembly adjacent the junction of said sections, said external member comprising a cylindrical portion surrounding said spout section, a plurality of bearing fingers extending upwardly and outwardly from said cylindrical portion and each of said fingers having a plurality of step-like bearing areas, and a plurality of locking fingers extending outwardly from said cylindrical portion.
4. A funnel construction comprising an assembly of a conical section and a spout section, an external member disposed outside of said assembly adjacent the junction of said sections, said external member comprising a cylindrical portion surrounding said spout section, a plurality of bearing fingers extending upwardly and outwardly from said cylindrical portion, each of said fingers having a plurality of step-like bearing areas including a lowest area, at least one intermediate area and a highest area, and a plurality of sets of locking fingers extending outwardly from said external member including a lowest set of locking fingers extending outwardly from the

bottom of the cylindrical portion, an intermediate set of locking fingers extending outwardly at about the lowest bearing areas level and the highest set of locking fingers extending outwardly at the bearing area level next below the highest bearing area level.

5. The funnel construction according to claim 4 in which the locking fingers of the sets of locking fingers other than the lowest locking fingers are disposed between the bearing areas.

MAX T. BENTZEN.
